UNITED STATES PATENT OFFICE.

THOMAS W. BRACHER, OF NEW YORK, N. Y.

SWEAT-BAND FOR HATS.

SPECIFICATION forming part of Letters Patent No. 380,175, dated March 27, 1888.

Application filed December 22, 1887. Serial No. 258,643. (No model.)

To all whom it may concern:

Be it known that I, THOMAS W. BRACHER, a resident of the city, county, and State of New York, have invented an Improved Sweat-Band 5 for Hats, of which the following is a specification.

The object of my invention is to provide certain useful improvements in sweat-bands for hats; and the invention consists in a sweat- 10 band having on its wearing side near its edge a flexible flat strip, which is held in place by stitches that pass through the band and over the edges and face of said strip, but not through it. This flexible strip will act to slightly 15 stiffen the edge of the band and also to ornament the sweat-band.

Reference is to be had to the accompanying drawings, forming part of this specification, in which—

20 Figure 1 is a face view of a portion of a sweat-band embodying my invention; and Fig. 2 is a cross-section on the line *c c*, Fig. 1, drawn on an exaggerated scale.

The letter *A* in the accompanying drawings represents a portion of a sweat-band for hats and caps.

25 *B* is a strip of flexible material placed along the wearing side *b* of the band *A* and near its edge, as shown. By "wearing side" I mean 30 the side of the band that rests against the head of the wearer. I preferably use flexible strips *B*, of straw or other substance, that con-

trast in color to the band *A*, by which means the band *A* is ornamented. The flexible strip *B* is held in position on the band *A* by means 35 of stitches *a*, which pass through the band *A*, over the upper and lower edges of said strip *B*, over its face, and over the edges of the band *A*, thereby binding the edge of the strip *B* and of said band and holding the strip as in a loop. 40 Thus none of the stitches pass through the strip *B*, and it is held to the band without injury. I may also place on or near the raw edge of the band *A* a spring or reed, *D*, which is held in place thereon by the stitches *a*, or 45 by stitches of the kind shown in Letters Patent No. 367,266, dated July 26, 1887, and granted to me. Although this strip *B* is flexible, it will nevertheless act to somewhat stiffen the edge of the band. By making the strip *B* thin 50 and flat, as shown, it will present a smooth wearing-surface to the head.

Having now described my invention, what I claim is—

A sweat-band having on its face or wearing 55 side *b*, near its edge, a flexible flat strip, *B*, held in place by stitches *a*, that pass through the band and over the edges and face of the strip *B*, as described.

THOS. W. BRACHER.
